UNITED STATES PATENT OFFICE.

FREDERICK SCHWANHAUSSER, OF JERSEY CITY, NEW JERSEY.

STEREOPTICON.

1,260,462.

Specification of Letters Patent. Patented Mar. 26, 1913.

Application filed November 30, 1917. Serial No. 204,647.

To all whom it may concern:

Be it known that I, FREDERICK SCHWANHAUSSER, a citizen of the United States, and a resident of Jersey City, in the county of 5 Hudson and State of New Jersey, have invented a certain new and useful Stereopticon; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 My invention relates to stereopticons and has for its object to provide an automatic plate shifting stereopticon wherein a large number of plates may be shown in sequence.

20 The invention also has for its object to provide a silently operated automatic plate shifting stereopticon, whereby the plates may be shifted with least possible noise and clatter. The invention also has in view the general improvements in stereopticons, advantages of which appear in the following 25 description or may be suggested upon the examination of the drawings. The invention may be embodied in different forms of construction or arrangement of parts. In 30 the drawings there is illustrated the preferred form of the structure, which, however is merely illustrative of the different forms that may contain the invention.

35 Figure 1 of the drawings illustrates a side view of the stereopticon selected for purposes of illustration. Fig. 2 illustrates a view of the operative parts, some of the parts of the stereopticon being removed for purposes of clearness. Fig. 3 illustrates the 40 propelling and step by step operating mechanism. Fig. 4 is an enlarged view showing the construction of the plate supporting parts and the means for yieldingly holding the plate carrier. Fig. 5 illustrates a view 45 of a plate holder. Figs. 6, 7 and 8 illustrate different positions of the plate in its transit between its normal position in the carrier and the position of exposure.

1, Fig. 1, is the supporting base on which 50 is supported, by means of standards 2, a

shaft 3 and a plate 4, a stereopticon 5. Plate carrier wheels 6 and 7 are also supported on the shaft 3. The shaft 3 is secured in the standards 2 by means of the key-bolt 8. The carrier wheels 6 and 7 are supported between collars 9 keyed to the shaft 3 by the key bolts 10 whereby the wheels are permitted to rotate on the shaft 3 but longitudinal movement along the shaft is prevented by the collars 9.

Means is provided for moving the carrier wheels 6 and 7 step by step and shifting the plates into and out of exposure. This is accomplished by the motor 11 which is also supported on the base 1 and through a set 65 of gear wheels located in a suitable gear box 12 operates to drive the gear wheel 13 at a comparatively slow rate of speed to give the desired period of exposure of the views found on the plates located in the plate holders. The gear wheel 13 is provided with means for engaging the carrier wheels from time to time to move the carriers step by step to bring the plates in the plane of the 70 position of exposure in succession. The arrangement is such that the wheels are moved alternately in the step by step operations.

In the form of construction shown, a dog 14 is secured to the gear wheel 13. The dog 14 may be in the form of a bent pin which 80 may be adjustably secured in the boss or socket 15 formed on or secured to the gear wheel 13, while the wheels 6 and 7 are provided with as many pins 16 as there are places in the wheel carriers for the plates. 85 When the wheel 13 moves half way around or 180°, it engages a pin of one or the other of the wheel carriers to move it one step forward. The wheels 6 and 7 being placed on opposite sides of the wheel 13, the dog 14 90 will move the carriers alternately in the step by step movements thus produced. The dog engaging the pins in succession will bring the plates of the carriers in the plane of position of exposure, whereupon the 95 plate from one carrier may be brought into position of exposure, while the plate of the other carrier is being withdrawn from the position of exposure. Each wheel carrier is held in position at the end of each of its 100

step by step movements by the spring 46 which is secured to the plate 4 and which terminates in a V-shaped engaging end 47 that is yieldingly placed between a pair of adjoining pins 16. The spring 46 operates to yieldingly hold the wheel carrier with which it is associated when the plates are brought in the plane of the position of exposure.

10 The gear wheel 13 is also provided with means that operate to shift the plates to and from the position of exposure. In the form of the structure shown, the gear wheel 13 is provided with a cam member 17 that is secured to the under side of the gear wheel. Levers 18 are supported in brackets 19 that are located on the base 1. The levers 18 may be provided with roller bearing members 20 that roll on the surface of the cam 17 as the gear wheel 13 is rotated. Links 21 are connected to the ends of the levers 18, and also to the arms 25 secured to the vertical moving rods 22 that pass up through the plate 4 and guiding sleeves 23 which are secured to the plate 4. Springs 24 are located intermediate the plate 4 and the arms 25. The springs 24 operate to yieldingly press the rods 22, the links 21 and the levers 18 downward and to press the 25 rollers 20 against the surface of the cam 17 when it is in position to engage one or the other of the rollers 20. Arms 26 are adjustably secured to the upper ends of the rods 22. The arms 26 are provided with 30 cam shaped hooks or dogs 27 for engaging the plates of the carrier. As the rollers 20 move off from or on to the cam 17, the cam 17 operating to raise the cam hooks 27 upward, while the springs 24 operate to draw 35 the cam hooks downward and push the rods 22 and links 21 down.

The cam hooks 27 operate to shift the plates from their normal positions in the wheel carriers to the position of exposure 40 and return them at the expiration of the period of exposure to their positions in the wheel carriers.

The plates 28 having the views that it is desired to present on a suitable screen, are 45 supported in holders 29. Each holder 29 is provided with a U-member 30 having a cylindrical shaped enlargement 31 which forms a guide in the rotary movements of the plate holder 29, the enlarged cylindrical 50 portion being provided with the bearing pin 32. The plate holders are supported on the peripheries of the wheels 6 and 7 for pivotal movements of the plate holders. The pins 32 are located in teeth or fingers 33 55 having channels 34 in which the pins are placed. The pins 32 are secured in position relative to the fingers 33 and so as to permit rotary movements of the pins 32 and the plate holders, by the springs 35. The

springs 35 have lips 36 which may be readily forced away from the fingers 33 to permit the pins 32 to slip into the channels 34 where they are held by the springs 35. The enlarged cylindrical portion 32 of the plate holders are located between the fingers 33 60 and coöperate with the bearing pins 32 to hold the plate holders in radial lines with respect to the axis of the wheel carriers 6 and 7. The plate holders are normally supported so that they extend away from the 75 stereopticon 5. The inner legs of the U-member of the plate holders 29 normally rest against a rib 37 located concentric with the rim 38 to which the fingers 33 are attached or form a part of.

In order that the plates of the lower half of the wheel carriers may be held in their normal positions, semi-circular strips 39 are supported on standards 40 that are also secured to the base 1. The strips 39 are provided with lips 41 to prevent engagement with the outer edges of the plate holders. The plates are secured in the holders in any suitable manner. In the construction shown, the plate holders are provided with channel 85 members 42 that are secured as by brazing or welding to the legs of the U-member 30. The plates 28 are inserted in the channel members 42. Means is provided for securing the plates in the holders. One of the channel members 42 may be provided with a spring 43 having a lip 44 that extends over an outer corner of the plate. This will prevent the plate from slipping from the 90 holder.

In order that the plates located in the plate holders may be shifted so as to bring the plates in position of exposure by the cam hooks 27, the plate holders are provided with fingers 45 that extend from the enlarged portions 31. The cam hooks 27 operate upon the fingers 45 of the plate holders 29 in succession to lift the plate holders 29 and turn them on the pins 32.

The wheel carriers 6 and 7 being located 105 on opposite sides of the stereopticon 5, a plate is swung first from one carrier into position of exposure and returned, while a plate from the other carrier is being swung into position of exposure. By this arrangement, a very short period will expire between the exposure of consecutive views, for one or the other of the wheel carriers may be shifted in its step by step movement by the operation of the dog 14, while a plate from 110 the other carrier is being exposed, and moreover, when one roller 20 is being released by the cam 17, the other roller 20 is being forced down. Also by this arrangement, a 115 large number of views may be presented in succession without materially increasing the size of the outfit. Twice the number of views may be presented in succession with 120

out materially increasing the size of the stereopticon and its automatic arrangement for shifting the views. Furthermore, by this arrangement either one or two wheel carriers 5 may be used by merely changing the cam 17 to cause reciprocatory movements of the cam hook 27 to shift the plates in succession from and to the positions of exposure, the wheel carrier being moved each step during 10 the interval between the reciprocatory movements of the plate from and to the position of exposure. Also the wheel carrier being rotatable about the horizontal axis, the apparatus may be contained in a small 15 volume since the larger dimensions of the plate carrier are located in a vertical plane and beside the stereopticon.

The cam hook 27 operates to shift the plates from their normal position in the carrier wheels to the position of exposure and return the plates with the least possible noise and so that the plates will not be dropped during their transit to and from their position of exposure. The cam hooks 25 27 are provided with a cam surface extending from the under side of the hook to the top of the hook. The outer ends of the cam hooks 27 pass close to the point of connection and fit in between the fingers 45 and the leg 30 of the U-member 30 of which the enlarged portion 31 forms a part. They slide from the fingers 45 to the legs of the U-members 30, or vice versa. When the plate is being returned to its normal position in the carrier 35 as shown in Figs. 6, 7 and 8, the fingers 45 are placed in such a position with reference to the leg of the U-member 30 that the cam hooks 27 will readily slide from one to the other whereby the plate holder will be held by the cam hook and movement due to 40 gravity, that is, dropping of the plate during its transit will be avoided. During the downward movement of the cam hook 27, the finger 45 slips over the under surface of the hook until the nose of the hook passes and practically fits into the space between the finger 45 and the leg of the U-member, and then the leg of the U-member rests upon the outer surface of the cam hook 27. Upon 45 further lowering of the cam hook 27, the plate is allowed to come down into position of exposure, where if it is desired, it may rest upon the top of the cam hook or may rest upon any other suitable device such as a cushion bracket or a bracket having a cushion thereon.

At the expiration of the period of exposure, the cam hook 27 is raised which raises the plate and as the cam hook 27 passes from the leg of the U-member to the finger 45, the plate is again held by the cam hook to prevent dropping of the plate in its rotation on the pin 32. Further movement of the cam hook 27 allows the plate holder to rotate

down until the leg of the U-member rests 65 upon the rib 37. By this arrangement of parts, the plates are noiseless in their movements back and forth to and from the position of exposure before the stereopticon 5.

I claim:

1. In a stereopticon, a carrier rotatable about a horizontal axis, plate holders rotatably secured in the periphery of the carrier, means for moving the carrier step by step to bring the plates in the plane of the position 75 of exposure in succession, means for swinging the plates into the position of exposure.

2. In a stereopticon, a pair of carriers rotatable about the horizontal axis, plate holders pivotally supported in the peripheries of 80 the carriers, means for moving the carriers step by step, the step by step movements of one carrier alternating with the step by step movements of the other carrier to bring the plates in succession in the plane of the position of exposure, means for moving the plates in the position of exposure, the plates of one carrier being moved to and from the position of exposure, while the plates of the other carrier are moved from and to the position of exposure. 85

3. In a stereopticon, a carrier, plate holders pivotally supported in the carrier, means for moving the carrier step by step to bring the plates in the plane of the position of exposure in succession, the plate holders having fingers, a cam hook for sliding along the fingers and the plate holders to move the plates into positions of exposure. 95

4. In a stereopticon, a carrier, plate holders pivotally supported in the carrier, means for moving the carrier step by step to bring the plates in the plane of the position of exposure in succession, the plate holders having fingers, a cam hook for sliding along the fingers and the plate holders, the nose of the cam hook fitting between the fingers and the plate holders to prevent the dropping of the plates in their transit to and from the position of exposure. 100

5. In a stereopticon, a pair of carriers, plate holders mounted in the peripheries of the carriers, means for moving the carriers alternately in the step by step movements to bring the plates in the plane of position of exposure in succession, the plate holders having fingers, cam hooks slideable along the fingers and the plate holders to bring the plates of one carrier alternately with the plates of the other carrier into position of exposure. 105

6. In a stereopticon, a carrier, plate holders pivotally supported in the carrier, means for moving the carrier step by step to bring the plates in the plane of the position of exposure in succession, the plate holders having fingers, a cam hook for sliding along the fingers and the plate holders, the nose of the cam hook fitting between the fingers and the 115

plate holders to prevent the dropping of the plates in their transit to and from the position of exposure, and a cam for operating the cam hook.

5. In a stereopticon, a pair of carriers, plate holders mounted in the peripheries of the carriers, means for moving the carriers alternately in the step by step movements to bring the plates in the plane of position of 10 exposure in succession, the plate holders hav-

ing fingers, cam hooks slideable along the fingers and the plate holders to bring the plates of one carrier alternately with the plates of the other carrier into position of exposure, and a cam for operating the cam hooks.

In testimony whereof, I have hereunto signed my name to this specification.

FREDERICK SCHWANHAUSER.
